CLAIM

The ornamental design for a wireless wall console, as shown and described.

DESCRIPTION

FIG. 1 is a perspective view of an embodiment of a wireless wall console showing our new design;

FIG. 2 is a front view thereof;

FIG. 3 is a right side view thereof;

FIG. 4 is a left side view thereof;

FIG. 5 is a rear view thereof;

FIG. 6 is a bottom view thereof; and,

FIG. 7 is a top view thereof.

The broken lines showing the buttons, cover, and mounting structure as shown in FIGS. 1-7 are directed to environment and are for illustrative purposes only; the broken lines form no part of the claimed design.
